SELECTIVE HYDROGENATION OF DIOLEFINS WITH COPPER CHROMITE CATALYST

Francis William Kirsch, Wilmington, Del., and Sol W. Weller, Drexel Hill, Pa., assignors to Houdry Process Corporation, Wilmington, Del., a corporation of Delaware

No Drawing. Filed Oct. 9, 1958, Ser. No. 766,194

11 Claims. (Cl. 260—677)

The present invention relates to selective hydrogenation of diolefins in hydrocarbon streams containing monoolefins and is especially concerned with selective conversion of butadiene contaminant in butene charge stocks employed in alkylation processes for production of aviation and motor gasoline. The invention, in certain of its aspects, also is applicable to selective conversion of diolefins, particularly C₄ diolefins, to monoolefins; as for example in production of butylenes for use in synthetic "Butyl" rubber or for other uses.

The C₄ fraction employed in alkylation processes is principally that obtained from thermal or catalytic cracking of higher boiling hydrocarbons or from a hydrocarbon coking operation. Such C₄ fraction may generally contain in the order of about 0.3 percent and up to about 1% or more of diolefin; the C₄ fraction from a cracking operation rarely contains as much as 2% of diolefin. Even this small content of diolefin in the feed for the alkylation process has been widely recognized as being extremely undesirable for the one reason, among others, of the greatly increased consumption of acid made necessary thereby, as a result of forming tarry acid-diolefin condensation products, adversely affecting the over-all economics of the alkylation process. Several suggestions for the conversion or removal of the diolefins from hydrocarbon mixtures also containing monoolefins have not proved attractive, because of accompanying concomitant disproportionate loss of monoolefins in the treated product, and high operating and investment costs.

In the case of a C₄ fraction derived from a coking operation which may contain even higher proportions of diolefins, going up to 5% or more, the problem is even more acute, and the use of such fractions for alkylation has been largely avoided.

Among the objects of the present invention is the provision of an improved process for selective conversion of C₄ or C₅ diolefins in a monoolefin-containing hydrocarbon fraction, wherein the monoolefin content is about 5 or more times the diolefin content, by catalytic hydrogenation of diolefins to more saturated product and with minimum hydrogenation of monoolefins in such fraction.

Such selective conversion of the diolefins is accomplished, in accordance with the present invention, by effecting the hydrogenation over a selected catalyst and under carefully controlled operating conditions. By this controlled operation the butadiene content of a C₄-olefin-containing fraction can be lowered to 0.1 weight percent or less and with a net loss of less than about 1% of butenes.

The process of the invention involves hydrogenation of a C₄ or C₅ hydrocarbon fraction comprising monoolefins and which contains a minor quantity of diolefins, over catalyst comprising copper-chromite; such hydrogenation being effected at a temperature in the range of about 125 to 250° F., and at pressures of about 1 to 20 atmospheres. The hydrogen added in the process is maintained as low as possible but at least in excess of the stoichiometric requirement for full conversion of the diolefins to monoolefins. In practice generally as applied, for example, to selective hydrogenation of an ole-

2

finic C₄ fraction containing up to about 2% diolefins, hydrogen is employed in a ratio of at least about 1.5 mols per mol of diene in the hydrocarbon feed and generally not in excess of about 20/1. Space rate of hydrocarbon feed may be from about 1 to 15 volumes of hydrocarbon (determined as liquid) per hour per volume of the catalyst in the reactor. Substantially the same reaction conditions are applicable to C₅ hydrocarbon mixtures comprising a small quantity of C₅ diolefins, operating in the higher portion of the described temperature range and permissibly as high as 300° F.

While the greatest advantages of the described process are obtained in the treatment of olefinic C₄ hydrocarbon streams containing less than about 2% butadiene by weight 15 of total hydrocarbons, the process is also applicable, but not necessarily with equal results, to the treatment of olefinic C₄ fractions of higher diolefin content, such as a butane-butylene fraction obtained from a thermal coking operation which may include up to about 5-6% diolefins. A further application of the invention lies in 20 the treatment of a butylene-rich stream from a dehydrogenation process containing from a fraction of a percent up to 5% or more diolefin. For example, in the dehydrogenation of butane, for production of butadiene, particularly after separation of the product butadiene by fractionation and extraction, there still remains in the monoolefin-rich raffinate a small percentage of butadiene of 25 from about a fraction of a percent up to about 2%, depending upon the efficiency of the separation. This 30 small amount of butadiene cannot be economically recovered as such, and interferes with the possible uses of the raffinate, for instance as feed to alkylation. Some butadiene is also produced in those processes designed principally for conversion of butane to butene. If the 35 quantity of butadiene in the product is sufficiently great, say in excess of about 5%, its recovery by known procedures may be warranted. Smaller quantities of butadiene, as between about 3 to 5% may or may not be 40 worth recovering as such, depending upon recovery costs versus market demand and value. In either of the above instances, the enhancement of the butene product by selective hydrogenation of diolefins in accordance with the present invention, comes into consideration.

The selective hydrogenation of butadiene in a monoolefin-rich mixture by the present invention is more easily 45 accomplished and with greatest efficiency when the proportion of diolefin in the mixture is quite low, for example less than about 2%. In such instance catalytic hydrogenation under the described operating conditions 50 can be accomplished in isothermal or adiabatic reactor systems, and some variation from the optimum in process variables can be tolerated at the expense of some sacrifice in yield and purity of product. In the case of butene-rich hydrocarbon fractions containing a larger amount 55 of diolefin contaminant, more precise handling is needed for selective hydrogenation of the diolefin. Since the hydrogenation is an exothermic reaction and the relative quantity of heat evolved at the selected operating conditions will depend on diolefin content, care must be 60 taken to avoid the development of excessive temperatures which may give rise to undesired extensive hydrogenation of the monoolefin. Moreover, the hydrogen to diolefin ratio in the reaction must be carefully controlled. For these reasons, in the handling of hydrocarbon streams 65 containing a substantial proportion of diolefins, say in the order of more than about 2%, isothermal operation may be best. On the other hand, adiabatic type operation is possible if the hydrogen input is kept low, that is, not substantially in excess of stoichiometric requirement for conversion of the diolefins to monoolefins, hydrocarbon inlet temperatures are maintained in the lower 70 part of the advocated range, and provisions are made

for heat removal from areas nearer the outlet of the reaction zone, such as by cooling coils or in other known manner.

The copper chromite catalyst employed is one having a substantial surface area and accompanying high activity. Such catalyst may be prepared by incorporation of the copper and chromium oxides in a porous relatively inert support such as alumina, or by simultaneous formation of these oxides ($\text{CuO} + \text{Cr}_2\text{O}_3$) in the absence of a carrier from a copper and chromium-containing complex or compound, such as basic copper ammonium chromate to produce so-called "massive copper chromite." While the term "copper chromite" is here employed consistent with art terminology to describe catalysts containing these oxides of copper and chromium in various proportions approaching stoichiometric, it is to be understood that the finished catalyst in heat-treated and/or reduced state is not necessarily or entirely in the form strictly of the compound CuCr_2O_4 . The catalysts employed in practice of the invention contain oxides of copper and chromium in proportions furnishing substantially equal atom proportions of Cu and Cr, as from 0.7 to 1.3 mols of copper per mol of chromium, and have a surface area in bulk or supported form of not less than about $50 \text{ m}^2/\text{g}$.

The preferred operating range for selective hydrogenation of C_4 diolefin over the alumina-supported catalyst includes temperatures in the order of 150–225° F. and pressures of from about 75 to 250 p.s.i.g., employing hydrocarbon space rates from about one volume (determined as liquid) per hour per volume of catalyst upward, as up to about 10. Hydrogen is added somewhat in excess of the stoichiometric requirement for conversion of the diolefin to monoolefin as from 1.5 mols H_2 per mol diolefin in the charge up to about 20:1. As noted above, less severe operating conditions on the low side of the temperature range and lower hydrogen ratios in the described range are employed when the hydrocarbon charge contains more than several percent of diolefin. With higher activity catalyst having a surface area in the order of $80 \text{ m}^2/\text{g}$, or more, lower pressures can be employed as down to about 70 p.s.i.g. and, if desired, somewhat higher space rates may be employed as up to about 12 or 15, in the treatment of hydrocarbon streams containing less than about 2% diolefins.

EXAMPLE I

The catalyst employed in the several runs comprised approximately 10% CuO and 10% Cr_2O_3 by weight on activated alumina, prepared in the manner hereinafter designated. The charge stock had the following composition:

	Weight percent of hydrocarbon charge
Butane	59.1
Butenes	39.2
Butadiene 1,3	1.42

The catalyst was brought to reduced state and the reactor and contents brought to required pressure by circulation of hydrogen-rich gas. The described C_4 hydrocarbon charge was then cut in and passed over the catalyst contained in the fixed bed reactor at an average temperature and under the conditions set out in Table I below with the results therein reported.

Table I

Run No.	1	2	3	4
Conditions:				
Temperature, ° F. (avg.)	212	215	238	148
Pressure, p.s.i.g.	150	150	150	150

	Butane, Weight Percent	Butenes, Weight Percent	Butadiene, Weight Percent
Charge	58.6	40.2	1.10
Product at 146 hrs	60.5	39.4	0.03
Product at 108 hrs	60.4	39.6	0.00

To determine the frequency of purging that may be required, the operation was run continuously over the catalyst of Example I without intervening purge. It was found that after about 40 hours of such operation the activity of the catalyst began to decline significantly and at a continuously increasing rate in the next several hours.

It will be seen from the foregoing that at high hydrogen/diene ratios there was a considerable conversion of the monoolefins. From the standpoint of selectivity, best over-all results were obtained at approximately the conditions of Run #4. As the temperature is increased, the residence time should be accordingly reduced to maintain comparable selectivity as can be seen in comparing Runs 1 and 3. Reduction of butadiene to below about 0.01% of product is ordinarily not required for most purposes and is not advocated if this can be accomplished only at the expense of disproportionate extent of hydrogenation of the monoolefins.

The catalyst employed in the above example was prepared as follows:

(a) The water-absorption capacity of the activated alumina pellets (having a surface area of about $80 \text{ m}^2/\text{g}$.) was determined as being 47% by weight, so that it was predicted that 2000 grams of the pellets would absorb about 940 cc. of solution containing the required content 20 of copper and chromium. To obtain complete immersion of the pellets in the solution, a 50% excess of solution was employed, to provide a catalyst composed of 2000 parts Al_2O_3 , 258 parts of CuO and 242 parts of Cr_2O_3 .

(b) 1178 parts of $\text{Cu}(\text{NO}_3)_2 \cdot 3\text{H}_2\text{O}$ were heated until the crystals melted, dissolving the salt in its water of hydration. 480 parts of CrO_3 ($= 363$ parts Cr_2O_3) were dissolved in 375 parts water with warming and stirring. The molten copper salt solution was added to the chromic acid solution with stirring and the solution diluted with water to a total volume equivalent to that occupied by 1402 parts water.

(c) 2000 parts of the activated alumina pellets were immersed in the impregnating solution (b) and allowed 35 to soak therein for 1–2 hours. The pellets were then drained free of excess solution and dried in hot air for 2 hours at 275° F.

(d) The dried pellets were then calcined for 8 hours 40 at 1325° F. in a steam-air atmosphere comprising 20 mol percent H_2O .

Using the catalyst of Example I above, the activity and selectivity of the catalyst for butadiene hydrogenation without excessive hydrogenation of monoolefins in the feed, are maintained over long operating periods of several months or more, provided that the catalyst is periodically purged with hydrogenation. Such hydrogenation purge is believed to remove from the catalyst polymeric hydrocarbon materials which become deposited therein during the reaction. Thus in runs made over the described catalyst operating continuously on a two-shift period and overnight shutdown, the flow of hydrocarbons was discontinued during the shutdown and hydrogen flow continued at about the same rate as during the on-stream period (approximately 12 hours on stream and 12 hours on purge). In over twelve days' operation with the described intervening hydrogen purges, there was no significant loss in the activity or selectivity of the catalyst. The results obtained after about 146 hours of such operation (at about 175–180° F. average hydrocarbon inlet temperature, 150 p.s.i.g., 3 LHSV, and 5 mols H_2 per mol diene in feed) are reported below:

The results obtained at 38 hours of such continuous operation (during which the temperature rose to 224° F.) are reported below:

	Butane, Weight Percent	Butenes, Weight Percent	Butadiene, Weight Percent
Charge.....	57.5	41.0	1.20
Product.....	60.6	39.0	0.02

Accordingly for those catalysts which begin to show loss of activity or selectivity in continuous running of about 36 to 48 or more hours, it is proposed to subject the same to a purge in hydrogen at about run temperature or somewhat below for 6 or more hours. The continuous running without purge should not be extended beyond the time that the catalyst begins to decline rapidly in activity, since once that the activity has been largely lost it has been found then impossible to restore the activity by the proposed hydrogen treatment.

Of course, with those catalysts which do not show appreciable activity decline on continuous operation of a week or more, the hydrogen purging step need not be practiced. When such catalysts eventually begin to decline in activity as a result of coke accumulation or other deactivating influences, these can be restored to activity by oxidative regeneration in air at about 700° F. or higher but short of damaging temperatures.

Prior to going on stream in treatment of hydrocarbons with fresh catalyst or with regenerated catalyst, the catalyst should be first reduced in hydrogen at temperatures above about 180° F., and preferably no higher than 300° F., for one or more hours. It was found that lower reduction temperatures (150° F.) failed to initiate the desired activity in the catalyst for hydrogenation of diolefin at space rates of 3 LHSV or higher.

EXAMPLE II

The following example relates particularly to the treatment of a refinery C₄ fraction of higher diolefin content, such as one of the following typical composition from mixed refinery sources:

	Mol percent
Butane	23.9
Isobutane	19.6
Butenes	51.1
Diolefins	5.4

The charge is fed to the catalyst, such as one described in the previous example, at a temperature of about 150-180° F. maintained in an isothermal reactor, at a pressure of 150 p.s.i.g. together with 2 mols hydrogen per mol of diolefin, the hydrocarbon charge rate corresponding to a liquid hourly volume space velocity of 5. Under these conditions the diolefins can be reduced to below 0.5% of product with less than about 3% net loss in monoolefins.

In the treatment particularly of hydrocarbon fractions of higher diolefin content in excess of about 2%, it is especially important that the hydrocarbon feed temperature be kept as low as possible to avoid the initiation of excessive exothermic temperature rise. Thus, it was found that even for a charge of only about 1% butadiene content, introduction of the hydrocarbon charge at 198° F. resulted in 82° F. temperature rise (at 5H₂:diene mol

ratio), while at an inlet temperature of 150° F., the temperature rise was only 17° F. (at 2.5H₂:diene mol ratio).

Obviously many modifications and variations of the invention as hereinbefore set forth may be made without departing from the spirit and scope thereof, and therefore only such limitations should be imposed as are indicated in the appended claims.

We claim:

1. The method of selectively hydrogenating diolefins present in minor quantity in a mixed hydrocarbon stream composed essentially of hydrocarbons in the range of 4-5 carbon atoms, said stream also containing monoolefins, which method comprises subjecting such mixed stream with added hydrogen to contact with active copper chromite catalyst having an initial surface area of not less than 50 square meters per gram, said contact being effected at temperatures in the range of 125-250° F. and at a pressure of 1 to 20 atmospheres.
2. The method according to claim 1 wherein said hydrocarbon stream is composed essentially of C₄ hydrocarbons.
3. The method according to claim 2 wherein said hydrocarbon stream contains up to about 2% by weight butadiene.
- 25 4. The method according to claim 1 wherein said hydrocarbon stream is one containing up to about 6% diolefins.
5. The method of selectively hydrogenating butadiene in a C₄ hydrocarbon fraction containing monoolefins in an amount of at least several times the butadiene content, which method comprises contacting the hydrocarbon fraction with a catalyst comprising oxides of copper and chromium wherein the Cu to Cr mol ratio lies between 0.7 to 1.3, said contacting being effected in the presence of free 30 hydrogen in quantity in excess of that stoichiometrically required for hydrogenation of the butadiene content of the charge to butene, and said contacting being at conditions including temperature in the range of about 150-250° F. and at pressure of 70 to 250 pounds per square 35 inch gauge.
6. The method according to claim 5 wherein said catalyst is unsupported copper chromite.
7. The method according to claim 5 wherein said catalyst comprises a porous inert carrier for said oxides.
- 45 8. The method according to claim 7 wherein said carrier is activated alumina.
9. The method according to claim 5 wherein said operating conditions include hydrogen to diene mol ratios of between 1.5 and 5.
- 50 10. The method according to claim 5 wherein the catalyst is subjected to a hydrogen purge in the absence of hydrocarbon feed for at least several hours between successive contacts with the hydrocarbon fraction.
11. The method according to claim 5 wherein said catalyst prior to hydrocarbon contact is treated in flowing hydrogen gas at above 180° F. for at least 6 hours.
